UNITED STATES PATENT OFFICE.

KENNETH F. COOPER, OF GREAT NECK, NEW YORK, ASSIGNOR TO AMERICAN CYANAMID COMPANY, OF NEW YORK, N. Y., A CORPORATION OF MAINE.

METHOD OF AND APPARATUS FOR FUMIGATING.

Application filed January 25, 1921. Serial No. 439,784.

To all whom it may concern:

Be it known that I, KENNETH F. COOPER, a citizen of the United States, residing at Great Neck, in the county of Nassau and State 5 of New York, have invented certain new and useful Improvements in Methods of and Apparatus for Fumigating; and I do hereby declare the following to be a full, clear, and exact description of the invention, such as 10 will enable others skilled in the art to which it appertains to make and use the same.

This invention relates to a process for the application of volatile liquid fumigants such, for example, as liquid hydrocyanic 15 acid, and to an apparatus for carrying out such application, and has for its object to provide a process and apparatus which will be more effective and more economical in use than those heretofore proposed.

With these and other objects in view, this invention consists in the novel steps and combinations of steps constituting the process, and in the novel combinations of parts constituting the apparatus, all as will be 20 more fully hereinafter disclosed, and particularly pointed out in the claims.

In order that my invention may be more clearly understood, it is said:

In fumigating with liquid hydrocyanic 30 acid or similar volatile fumigant for the extermination of insects, rodents and various other pests, the following is a description of one method of procedure, as at present carried out.

The volume of the space to be fumigated 35 is first accurately determined, and from this volume the actual and effective dosage of the liquid required is arrived at by referring to a previously prepared chart. The enclosure 40 is then made as nearly gas-tight as possible, as, for instance, in the case of a room the windows being tightly closed and latched, and all doors and ventilators closed and sealed. The dosage of the liquid is then 45 carefully measured and atomized into the enclosure through any convenient opening. In this atomized state the fumigant evaporates with greater or less velocity, depending on the temperature, degree of atomization and other similar factors.

The opening is then closed and sealed as quickly as possible, and the room is allowed to remain in this condition for a sufficient time until killing has been effected, this time

depending upon the size and shape of the 55 room, and the temperature at which the fumigation is carried out.

For instance, in a very large room with a great many irregularities, such as nooks and 60 alcoves, and when the temperature is comparatively low, the time required for effective fumigation is longer than it would be under more favorable conditions. In the case of a theatre where the outline of the space of the room is very irregular, and in 65 the holds of vessels where this same condition applies, the time required for effective fumigation often takes several hours. It must also be borne in mind that in order to get an effective killing of all the pests it is 70 absolutely necessary to get a uniform distribution of the gas throughout the whole space. In the case, for instance, one is fumigating for the purpose of killing flies, the 75 gas must permeate in sufficient concentration to the ceilings, walls and cracks where these flies are found, while in the case of rats, the gas must enter into their holes and hiding places in the required concentration.

With the equipment heretofore proposed it 80 is necessary to depend for this distribution on the rate of diffusion of the gas of the particular fumigant employed, but since the temperature at which such work is usually carried out may be below the boiling point 85 of the fumigants employed, and further, due to the high heat absorption incident to vaporization of the fumigants, and the consequent cooling effect on the vapor, the subsequent diffusion may be very materially 90 slowed down. Regardless of how careful one is in stopping up the leaks in such an enclosure, there is always a very large percentage of leakage of the gaseous material 95 before complete diffusion has been effected. An excessive dosage may be therefore required so as to procure the desired final effective concentration of the poisonous gas in places remote from the point of application, and such an overdose, of course, necessitates a material extra cost of valuable 100 fumigating material.

Another serious disadvantage of this method of fumigating is the long time required to obtain the uniform effective concentration. This is a very important factor in the fumigation of busy office buildings and factories which are in constant use, and 105

where vacating necessitates great inconvenience and expense. It is therefore desirable in work of this sort that the fumigant be introduced in a gaseous form, under such conditions as to facilitate rapid mixing and diffusion so that a uniform effective concentration of the killing gas may be had in the shortest possible time, and I am here disclosing a means of accomplishing the desired results in a unique and effective manner.

Liquid hydrocyanic acid, because of its very poisonous nature, has not been quantitatively studied by the physicist. Its boiling point is approximately 80° F. while its latent heat of evaporation is relatively high, but not quite as much as that of water. It freezes to a solid at approximately 0° F. and at ordinary summer temperature when poured on a flat surface, it evaporates so rapidly that it solidifies, due to the cooling incident to the rapid evaporation.

It has been found not to be a satisfactory method of application to pour out the liquid on a floor and permit it to evaporate, because the material freezes and then slowly gasifies which greatly prolongs the time required for thorough fumigation. When atomized it rapidly evaporates, but the vapor is so cold that it tends to hang around the lower parts of the space being fumigated and diffusion is consequently slow.

In my improved apparatus I take into account these physical properties of liquid hydrocyanic acid and eliminate the disadvantage of using the material as an ordinary fumigant by gasification before application. In the first place, realizing that fumigation must be carried on rapidly in order to utilize equipment and labor most effectively, it is necessary that any scheme of evaporation be such that considerable quantities of the liquid can be changed to gas in a very short space of time. In view of the very considerable heat absorption during evaporation, I propose to perform this function by providing a large storage or reservoir of heat, which storage is continuously supplied directly through the burning of fuel, or by the application of steam, or otherwise, and to draw upon this heat storage as required for the rapid evaporation of successive dosages of liquid hydrocyanic acid.

One example of such storage would be a hot water system or a steam boiler in which I continuously supply heat by combustion at a limited or reasonable rate, and draw off this heat as needed for performing my evaporation of the liquid hydrocyanic acid. I may also use heated oil or other similar mediums for the storage of the necessary quantities of heat.

This enables me not only to evaporate considerable quantities of hydrocyanic acid in a very short time but at the same time keeps the source of heat, such as burning

fuel, at some distance from the containers and gasifying equipment, which is a decided advantage when one considers the inflammability of the hydrocyanic acid. It also permits taking advantage of using a comparatively low-temperature source of heat for the vaporization, such as low pressure steam or even hot water.

I can also accomplish the same result by using as my evaporator, a metal container of heavy construction, which in itself can store up large quantities of heat and deliver the same up to the liquid in comparatively short time. But, on the other hand, hydrocyanic acid gas heated in contact with metal is decomposed rather readily, and it is, therefore, of decided advantage to carry on its evaporation through such medium as hot water or steam to prevent overheating. Direct heating over a flame in a thin-walled evaporator likewise possesses the disadvantage of having to use a flame of considerable intensity in order to rapidly evaporate the liquid hydrocyanic acid, and it would be necessary to control this flame very sharply so as to avoid undue heating of such apparatus between successive doses. This of necessity would complicate the apparatus and introduce an element of danger because of the unskilled character of the labor usually doing the work. On the other hand, the indirect system of evaporation which I have proposed eliminates these difficulties by permitting the source of heat to act with greater uniformity and at the same time permitting the ready withdrawal of heat from the storage vessel as needed in the vaporizer.

In the application of gaseous hydrocyanic acid, it is frequently necessary to carry it through comparatively long pipe lines or hose lines to reach the point of fumigation. Since the vapor taken off of the boiling liquid is saturated and will condense with any drop in temperature, and since considerable fumigation is done at temperatures below the boiling point of this liquid, it is necessary if accurate dosages are to be secured, to prevent such a condensation in the pipe lines used to convey the gas. While superheating of the vapor will eliminate this condensation to a degree, and I use this principle for certain cases of fumigation, I have found that under certain conditions such superheat is not always sufficient to avoid condensation. In these cases I find it of material advantage to prevent the condensation of the hydrocyanic acid to the liquid form, by introducing into said acid air or other inert gas along with the issuing stream of vapor, leaving the vaporizer.

Referring now to the accompanying drawings, forming a part of this specification in which like numerals designate like parts in all the views:

Figure 1 is a diagrammatic transverse

sectional elevational view of one form of apparatus suitable for carrying out the present method; and

5 Figure 2 is a detail sectional view of the heating chamber.

1 indicates a suitable frame, or bed, mounted upon the wheels 2, and carrying upon it in any suitable manner the tank 3, provided with the filling plug 4. The said tank 3 may be connected at or near its lowermost portion as by a pipe 5, provided with a valve 6, to the upper portion of the receiving tube or chamber 7. The said receiver 7 is preferably closed at its upper 10 end and provided with a stuffing box 8, through which passes the hollow tube or pipe 9, which is connected at its upper end by means of the hollow handle 10 with the tube or pipe 11. The said pipe 11 passes through the stuffing box 12 into the tubular member 13, which permits said pipe to move 15 up and down while maintaining a tight joint with the stuffing box 12. The lower end of the tube 13 is connected as by the pipe 14, provided with check valve 14^a, to the mixing chamber 15, as will be clear from the drawings.

Also mounted upon the frame 1 is a pump 16, provided with a piston 17 adapted to be actuated by the piston rod 18 and handle 19, and the said pump is connected as by the piping 20 with the upper end of the receiver 7, substantially as shown.

30 The apparatus as thus far disclosed, with the exception of the frame 1, wheels 2, and mixing chamber 15, is or may be substantially the same as disclosed in my copending application filed December 29, 1920, Ser. No. 433,876, and entitled "Fumigating apparatus."

35 A second pump 25 is mounted upon the frame 1, and provided with a piston 26 adapted to be actuated by means of the piston rod 27 and handle 28, and the said last mentioned pump is joined as by the piping 29 to the mixing chamber 15, see Figure 1. The pipes 20 and 29 may, if desired, be provided with suitable check valves 20^a and 29^a to permit the flow of 40 fluid away from the pumps 16 and 25 respectively, but preventing a return thereto.

45 The mixing chamber 15 is connected by a pipe 30 to the heating receptacle 31, which comprises a shell 32, provided with a pair of headers or partitions 33 and 34, forming a plurality of chambers 35, 36 and 37. The pipe 30 passes through the shell 32, and through the chamber 35, and communicates with the chamber 37, while communication 50 between the chambers 35 and 36, which are adapted to contain water, oil, or other heat storing medium, is provided by means of a plurality of tubes or pipes 38 passing through and secured in the headers or partitions 33 and 34, as will be clear from

Figure 2. A discharge pipe or hose 39 leads from the chamber 37 to any suitable form of atomizing nozzle 40, here shown as introduced through the wall or partition 41 into the enclosure 42 to be fumigated.

70 The valve 6 may be controlled by means of the rod 43 provided with the knob or handle 44, while 45 designates any suitable form of indicator such as is usually employed with apparatus of this general type, 75 which indicator is preferably secured to the receiver 7 substantially as shown.

Any suitable means may be provided for supplying heat to the receptacle 31, such, for example, as the liquid fuel burner 46, 80 carried below the said receptacle 31 by an extension 47 of the frame 1.

The mode of using the apparatus above described in carrying out the present method will be clear from the foregoing, but may 85 be briefly summarized as follows:

The tank or container 3 is first filled by removing the plug 4, filling the container by any approved method, and then again screwing plug 4 back into place. The handle 10 90 connected to tubes 9 and 11 is then adjusted to any desired position, depending on the dosage required and the valve 6 is opened, whereupon liquid from container 3 will flow into the receiver 7, and the entrapped air 95 previously contained in receiver 7 will be forced out through the tubes 9, 11, 13, 14 and 39. After the receiver 7 is completely filled with liquid, the valve 6 is again closed by re-

leasing the handle 44, and both the air 100 pumps 16 and 25 are brought into operation by means of the handles 19 and 28. The pressure supplied by the air pump 16 is communicated to the liquid contained in the receiver 7 through the pipe or tube 20, caus-

ing the liquid to pass through the tubes 9, 10 and 11 into the tube 13, then through the pipe 14 to the mixer 15, where it is combined with the compressed air from the pump 25, entering through pipe 29. The 110 mixture of air and liquid then passes by way of the pipe 30 to and through the space 37 around tubes 38, which space is heated by means of the heater 46 through the storage medium of hot water or other fluid contained in the chambers 35 and 36, and pipes 38. The liquid fumigant is here vaporized and the mixture of hot air and vapor passes through the pipe or hose 39 and nozzle 40 115 into the enclosure 42.

120 In practice the tube 9 may be adjusted up and down through the stuffing box 8, whereupon the indicator carried by said tube, not lettered, will indicate on the scale member 45 the position of the lower end of the tube 125 in the chamber 7. Knowing the position of this said lower end of the tube 9, the operator will know with accuracy the amount of liquid which will be forced out of the chamber 7 when air through the pipe 20 is forced 130

into the top of said chamber. This said predetermined amount of liquid, when forced out of chamber 7, enters the pipe 11 and the tube 13, and is forced from there into the 5 mixing chamber 15. The tube 13 is made larger than the tube 11 so that the latter may readily move up and down therein when the tube 9 is adjusted for measuring the fluid in the manner above disclosed. In the 10 chamber 15 the liquid is subjected to the pressure of air from the pipe 29 and is forced through the pipe 30 and into the spaces 37 between the pipes 38, see Fig. 2, which causes said air to mix with said liquid. Especially 15 is this the case when the said chambers 37 are heated from the tubes 38 and therefore, when the fumigant is forced out through the pipe 39 it is well mixed with air.

20 It is also evident from the method of operation previously described above that these parts may be somewhat rearranged. For instance, the measuring device described is but one means of obtaining the desired 25 result, and I am aware that I could employ any of several methods to do this measuring. It is further evident, in this particular case, for instance, that I might use but one air compressor and by suitable manipulation accomplish 30 the same purpose as the two compressors 16 and 25 shown.

It will be seen from the above disclosure that my process and apparatus is capable of meeting the peculiar and unusual demands 35 of the fumigating industry for the use of a volatile liquid fumigant. I have provided the necessary measuring equipment to insure accurate dosage of the liquid and in a simple and easy manner, I discharge this dosage 40 into a vaporizer which is so constructed that evaporation takes place very rapidly due to a considerable heat storage intimately connected with the vaporizer. This enables me to take the large dosages usually used 45 in this work and instantly evaporate them to gas, and, while the apparatus is being moved to a new position, to generate and store heat for use in the next application. By the present construction and process I store this heat 50 at moderate temperatures and so do not subject the fumigant to extremes of temperature with the accompanying danger of decomposition. The apparatus further is capable of superheating the gaseous fumigant, 55 but since only a limited amount of superheat can be safely carried in this vapor, I, at the same time, can reduce the dew point so as to avoid condensation of the vapor in the tube such as 39 carrying the same from the vaporizer to the point of application. 60 My apparatus is safe, inasmuch as I may have my source of heat entirely distinct and separate from the vaporizer and should leakage of the vaporizer occur, the liquid fumigant or its vapor are not likely to come into

contact with an open flame and cause fire or explosion.

I gain considerable rapidity of action by this process and apparatus, which is a very important factor, as the cost of labor constitutes a large percentage of the total cost of fumigation. This apparatus will further deliver very exact dosages, as it is completely flushed out at each discharge with an excess of warm air. From a small quantity of 75 vapor used, by mixing with a considerable portion of air in the apparatus itself, I obtain in consequence a very much quicker and thorough mixing of the fumigant in the space to be fumigated and consequently obtain a much quicker and effective application than where dependent upon the natural diffusion of cold vapors. As a consequence the spaces to be fumigated are out of service 80 for a minimum length of time. 85

The apparatus is comparatively cheap and simple to construct, and easily transported, which in certain cases is a decided advantage inasmuch as in the fumigation of fruit or other trees, or plants, it must be handled 90 often over loosely cultivated soil.

It is obvious that those skilled in the art may vary the details of construction and arrangement of parts constituting the apparatus, as well as the steps constituting the 95 process, without departing from the spirit of the invention, and therefore I do not wish to be limited to the above disclosure except as may be required by the claims.

What I claim is:

1. The process of applying a volatile liquid fumigant which consists in measuring a predetermined quantity of said fumigant in its liquid form; subjecting said measured liquid fumigant to pressure; admixing said measured fumigant with an inert gas under pressure; subjecting the mixture of gas and fumigant to heat in excess of that required for volatilization; and introducing the 105 heated vaporized fumigant into the space to be fumigated, substantially as described.

2. The process of applying a volatile liquid fumigant which consists in measuring said liquid; mixing air with the measured fumigant; subjecting the mixture thus obtained to a quantity of heat in excess of that required to fully vaporize said liquid; and introducing the heated mixture of vapor and air into the space to be fumigated, substantially as described. 115

3. The process of fumigating with a volatile liquid fumigant which consists in mixing an inert gas with said fumigant; providing a heat storage reservoir; passing said mixed gas and fumigant through said reservoir to vaporize and superheat the same; and introducing said superheated mixed gas and vapor into the space to be fumigated, substantially as described. 125

4. The process of fumigating with a vola-

- tile liquid fumigant which consists in measuring said fumigant; mixing said fumigant with air; supplying an additional quantity of heat to the mixture to vaporize and superheat the same; and introducing the superheated mixture into the space to be fumigated, substantially as described.
5. The process of fumigating with a volatile liquid fumigant which consists in mixing an inert gas with said liquid; providing a medium adapted to store and transmit heat; constantly supplying heat to said medium; subjecting a predetermined quantity of said mixed gas and liquid to the action of heat 10 thus stored to superheat the same; and introducing the superheated mixed gas and vapors into the space to be fumigated, substantially as described.
6. The process of fumigating with a volatile liquid fumigant which consists in providing a medium adapted to store and transmit heat; constantly supplying heat to said medium; measuring a predetermined quantity of the said fumigant; mixing air with 15 the fumigant; subjecting the mixture to the action of the heat stored in the said medium to vaporize and superheat the same; and introducing the superheated mixture into the space to be fumigated, substantially as described.
7. In a fumigating apparatus the combination of a supply tank adapted to contain a liquid fumigant; a vaporizer provided with a heat storing and transmitting medium and a fumigant receiving chamber; means adapted to supply heat to said medium; means adapted to deliver a predetermined quantity of fumigant from said tank 20 to said vaporizer; means to admix air with said fumigant before it enters said vaporizer; and means for transferring the vaporized mixture of air and fumigant from said vaporizer to the space to be fumigated, substantially as described.
8. In a liquid hydrocyanic acid fumigating apparatus the combination of a supply tank adapted to contain said acid; a vaporizer adapted to receive and store a sufficient quantity of heat to completely vaporize a predetermined portion of said acid and to 25 superheat said vapor; means adapted to supply said heat to said vaporizer; means adapted to transfer a variable predetermined quantity of said acid from said tank to said vaporizer; means adapted to mix an inert gas with said predetermined quantity of acid; and means for transferring the superheated mixture from said vaporizer to the space to be fumigated, substantially as described.
9. In a liquid hydrocyanic acid fumigating apparatus the combination of an acid supply tank; a receiver associated with said tank; a mixing chamber; means adapted to deliver a variable predetermined quantity of acid from said receiver to said mixing chamber; means for supplying air to said chamber; a vaporizer containing a medium adapted to receive and store a sufficient quantity of heat to completely vaporize said predetermined quantity of acid and to superheat the mixture of acid vapors and air; means for constantly supplying heat to said medium; and means for transferring said superheated mixture from said vaporizer to 30 the space to be fumigated, substantially as described.

In testimony whereof I affix my signature.

KENNETH F. COOPER.
